UNITED STATES PATENT OFFICE.

CLAUDIUS DORNIER, OF FRIEDRICHSHAFEN-ON-THE-BODENSEE, GERMANY, AS-
SIGNOR TO THE FIRM: DORNIER METALLBAUTEN GESELLSCHAFT MIT BE-
SCHRÄNKTER HAFTUNG, OF FRIEDRICHSHAFEN-ON-THE-BODENSEE, GERMANY.

METAL GIRDER FOR LIGHT METAL STRUCTURES.

Application filed February 17, 1923. Serial No. 619,696.

To all whom it may concern:

Be it known that I, CLAUDIO DORNIER, a citizen of Germany, residing at Friedrichshafen-on-the-Bodensee, Germany, have ⁵ invented certain new and useful Improvements in Metal Girders for Light Metal Structures, of which the following is a specification.

My invention relates to metal girders and ¹⁰ more especially to a metal girder intended for low weight structures for air craft construction. It is an object of my invention to provide a structural element of high strength and low weight which can be manufactured at low cost.

The side walls of the box-shaped girder according to my invention are provided with oppositely located apertures having inwardly directed flanges which may extend ²⁰ so far inside that they can be connected with each other by riveting or welding. The apertures may have any desired shape. It is, however, preferable to provide apertures of substantially equal shape and diameter. ²⁵ The inter-connected flanges of the apertures form hollow connecting members, the axis of which extends about at right angles to the longitudinal axis of the girder.

The connection of the two side walls in ³⁰ the planes of the girths may be effected in any desired manner, for instance, by means of a panel, but it is preferred to provide the side walls in the girth plane with outwardly directed flanges and to connect these latter ³⁵ with each other by a sheet-metal strip. In view of the comparative thinness of the sheet-metal employed in the construction of aircraft this affords favorable conditions of assembling and warrants a good accessibility of the rivet seams. The longitudinal edge portions of the side-walls are preferably bent outwards at an obtuse angle. The sheet-metal strips are preferably grooved or channelled.

⁴⁰ In the drawings affixed to this specification and forming part thereof a girder embodying my invention is illustrated by way of example. In the drawing

Figure 1 is a cross section and

Figure 2 a side elevation. ⁵⁰

Referring to the drawing, the girder consists of two side walls 1 and 2 provided with circular apertures having inwardly directed flanges 3 and 4 which are fastened to each other by rivets 5. If weldable metal ⁵⁵ is used, the flanges may be connected with each other by spot welding. The longitudinal edge portions of the walls 1 and 2 are bent outwards forming flanges 6 and the rims 7 of these flanges are again bent in ⁶⁰ such a manner, that the flange rims 7 disposed on the same side converge as shown in Figure 1.

The lower boom consists of a plain strip ⁶⁵ 8 of sheet-metal, while the top boom 9 is formed of a sheet-metal channel.

I wish it to be understood that I do not desire to be limited to the exact details of construction shown and described, for obvious modifications will occur to a person ⁷⁰ skilled in the art.

I claim:

1. A light sheet metal girder comprising two juxtaposed apertured side walls and inwardly directed flanges surrounding the ⁷⁵ apertures of said walls, said flanges being rigidly connected.

2. A light sheet metal girder comprising two juxtaposed apertured side walls, inwardly directed flanges surrounding the apertures of said walls, said flanges being rigidly connected and plate strips riveted to and connecting adjoining free edges of said side walls. ⁸⁰

3. A light sheet metal girder comprising two juxtaposed apertured side walls, inwardly directed flanges surrounding the apertures of said walls, said flanges being rigidly connected, flanges extending substantially at right angles from the longitudinal edges of said side walls and plate strips riveted to and connecting the latter flanges on adjoining edges. ⁸⁵

4. A light sheet metal girder comprising two juxtaposed apertured side walls, inwardly directed flanges surrounding the apertures of said walls, said flanges being rigidly connected, obtusely angular flanges ex-

tending substantially at right angles from the longitudinal edges of said side walls and plate strips riveted to and connecting the latter flanges on adjoining edges.

5. A light sheet metal girder comprising two juxtaposed apertured side walls and inwardly directed flanges surrounding the ap-

ertures of said walls, the flanges of one side wall extending in overlapping relation to the flanges of the other side wall and being rigidly connected therewith. 10

In testimony whereof I affix my signature.

CLAUDIUS DORNIER.
